UNITED STATES PATENT OFFICE

EDMUND C. MORGAN, DECEASED, LATE OF NEW YORK, N. Y., BY OLIVE EUGENIE MORGAN, EXECUTRIX, OF NEW YORK, N. Y.

RAIL CLAMP FOR LOADING MACHINES

Original application filed August 14, 1917, Serial No. 186,118. Divided and this application filed September 13, 1928. Serial No. 305,748.

This invention relates to clamping means and more particularly to rail clamps, it constituting a division of the application of Edmund C. Morgan, serially numbered 186,118, filed August 14, 1917.

It contemplates more especially the provision of a simple and readily associable clamp mechanism which is particularly adaptable to rails for enabling the shifting of wheeled frames thereon, although it may be employed with equal advantages for other purposes.

One object of the present invention is to simplify the construction and improve the operation of devices of the character mentioned.

Another object is the provision of an exceedingly simple clamping mechanism having a binding effect proportional to the force exerted thereon.

Still another object is to provide a clamping mechanism which is readily assembled and dismantled for instant manipulation.

A further object is to provide a clamping mechanism which is instantly adjustable for gripping application at any predetermined position along a member.

A still further object is the provision of a clamping mechanism in combination with a guided wheeled frame for effecting the shifting thereof.

Still a further object is the provision of a lever in association with an eccentric to cooperate with jaws for effecting the instant clamping of a member therebetween.

Other objects and advantages will appear from the following description of an illustrated embodiment of the present invention.

In the drawings:

Figure 1 is a perspective view of a device embodying features of the present invention.

Figure 2 is a sectional view taken substantially along line 2-2 of Figure 1.

Figure 3 is a fragmentary sectional view taken substantially along line 3-3 of Figure 2.

Figure 4 is a plan view of a machine which is rendered movable with reference to the device disclosed in Figure 1.

Figure 5 is a view in elevation of the machine disclosed in Figure 4.

Figure 6 is a fragmentary enlarged plan view of the rearward portion of the machine disclosed in Figure 4.

The structure selected for illustration comprises an attachment member, in this instance a rail 10 of standard construction having the usual base flange 11 with its inclined surfaces 12, although any other type of attachment member may be employed with equal advantage. In order to effect the fixed association of a clamp to the member 10, there are provided spaced jaws 13 and 14, in this instance two, which terminate in parallel disposed shanks 15 disposed adjacent the edges 16 of the base flange 11.

The shanks 15 are provided with aligned bores 17 which receive a rotary member such as a shaft 18 therethrough, the shaft 18 being provided with circular portions 19 and 20 whereon the jaw shanks 15 are journaled. As shown, the jaws 13 and 14 terminate in integral gripping faces 21 and 22, respectively, inclined to correspond with the faces 12 of the base flange 11 to effect contact therewith for guidance by the vertical edges 16 of the member 10. Intermediate the circular portions 19 and 20, the shaft 18 is provided with an eccentric 23 constituting a camming surface, in this instance formed integral with the shaft 18.

Rotary movement of the shaft 18 in a predetermined direction will bring the jaw faces 21 and 22 into engagement with the upper surfaces 12 of the base flange 11 of the rail 10 and the eccentric cam 23 into engagement with the lower or sustaining surface thereof, thereby securely fixing the clamp to the rail 10. In order to expedite the rotation of the shaft 18 to effect the ready association and disassociation of the clamp with the attachment member or rail 10, an arm or lever 24 is provided for association with the circular portion 19 of the shaft 18, it being detachably or otherwise fixed thereto as commercial practice may dictate so that the free extremity 25 thereof may be utilized for adjusting the clamp with respect to its attachment member, in this instance the rail 10.

So that the jaw 14 may be retained on the circular portion 20 of the shaft 18 without

preventing the rapid removal thereof, a U-shaped retainer 26 is provided for detachable association with the extremity of the shaft 18. To this end, the legs 27 of the retainer 26 are provided with inwardly projecting confronting ribs 28 which enter correspondingly shaped slots 29 in the periphery of the circular portion 20. With this arrangement, the retainer 26 is diametrically slideable relative to the shaft 18 for instant disassociation to enable the jaw 14 to be removed so that the clamp may be secured in position to the rail 10. The jaw 14 and the retainer 26 may then be replaced so that any force exerted in one direction on the arm 24 will cause the base flange 11 to be clamped between the jaws 13 and 14 and the eccentric 23.

The clamp will then be held firmly to the rail in position so that the greater the force on the arm or lever 24, the effectiveness of the grip will be proportional therewith. To release the clamp, it is only necessary to move the arm 24 in a reverse direction a slight distance whereupon the clamp may be shifted along the rail 10 or be dismantled for association in a new position. It is thus apparent that a simple, effective and readily adjustable clamp has been provided, and such may be employed for varied uses as will readily appear from the following description of a specific application.

The invention may be advantageously used in connection with loading machinery or other mechanism mounted on a wheeled frame to effect the movement thereof along a predetermined path determined by rails constituting the traction means. In this instance, the loading mechanism is of the type more specifically described in the parent application filed in the name of Edmund C. Morgan bearing Serial Number 186,118 wherein a forward truck 30 and a rear truck 31 have their adjacent ends interconnected to carry conveyor sections 32 and 33, respectively. The forward conveyor section 32 may be swung laterally, as indicated by broken lines in Figure 4, and vertically, similarly indicated in Figure 5.

The frames 30 and 31 are carried by wheels 35 and 36, respectively, carried on spaced axles 37 and 38, respectively, which are journaled in side members of the truck frames 30 and 31. The wheels 35 and 36 are guided by rails 10 of standard construction constituting the traction means therefor. The forward axle of the rear truck 31 is driven by a motor 39 provided with a pinion 40 which meshes with a gear 41 secured to the forward axle 38, the motor 39 being supported by a vertical stud bolt 42 which is secured to a bottom plate 43 to engage a lug 44 formed integral with the motor casing 39. Spring means envelope the stud bolt 42 to resiliently mount the motor 39 in the customary manner. The motor 39 drives the rear truck 31

in synchronism with a forward motor 45 geared to the wheels 35 of the forward truck 30, through suitable controllers 46, to enable the device to be moved to a point where loading is to be carried on.

In order to shift the machine forwardly and rearwardly during loading operations, a shaft 47 is journaled in bearings 48 and 49 carried by side members 50 and 51. A series of drums 52, 53, 54 and 55 are secured to the shaft 47 which is driven by a motor 56 secured to the bed plate 43 of the truck frame. The motor 56 has the armature thereof provided with a pinion 57 which meshes with reduction gearing 58, 59 and 60, the latter being fixed to the shaft 47 to effect the rotation thereof.

Forwardly extending cables 61 are secured to drums 52 and 55, and rearwardly extending cables 62 are similarly secured to the peripheries of drums 53 and 54, with the ends thereof secured, respectively, to wall jacks 63 as at 64, and to the arms or levers 24 of the clamps secured to the rails 10 in a manner described in detail *supra*. The inner ends of the wall jacks 63 are pivoted together at 65 with their outer ends pivoted to blocks or shoes 66 arranged to bear against the walls 67 of the mine chamber. The inner ends of the wall jacks 63 are inclined forwardly so as to form a toggle to force the jacks into contact with the walls of the chamber and thereby prevent rearward movement.

The cables 62 having their ends secured, as previously described, to holding arms 24 of a clamping device embodying features of the present invention, it will be apparent that rotation of the motor 56 in one direction will wind the cables 61 upon their drums 52 and 55, while cables 62 will be unwound or paid out from their drums 53 and 54 to move the wheeled frame forwardly. Reversing the motor 56 will move the frame in a reverse direction so that forward and rearward movement can be selectively effected.

It should be particularly noted that the anchoring mechanism for the forward ends of the ropes 61 and the anchoring mechanism for the rear ends of the ropes 62 are particularly adapted to the operation of a loading machine in which a load is gathered by reciprocating the machine along a mine track rectilinearly. It can readily be seen by referring to Figs. 4 and 5 that the gathering mechanism 32 is provided with a beveled nosepiece 68 which may be located in longitudinal alignment with the mine track M as shown in full lines in Fig. 4, or shifted to the dotted line positions 69 and 70, but whether the gathering mechanism is extended longitudinally of the mine track or angularly relative thereto, the loading operations are all by rectilinear forward movements of the gathering mechanism.

When the forward ends of the ropes 61 are

anchored to the wall jacks 63 and the rear ends of the ropes 62 are connected to the rail clamps the rope-winding mechanism shown in Fig. 6 may be operated so as to secure reciprocating movements of the gathering mechanism.

While the forward ends of the ropes 62 may be connected to rail clamps of the type shown in Fig. 6, it is preferred to connect

10 the forward ends of the ropes 61 to wall jacks as shown in Figs. 4 and 5, because the loading machine is of a type permitting support by means of the floor shoe 71 with the forward wheels of the forward truck off the mine track. It will therefore be evident that the range of operations of the gathering mechanism may be extended beyond the forward end of the mine track. Therefore when such operations are extended beyond

20 the forward end of the mine track the forward ends of the ropes 61 may nevertheless be anchored by means of the wall jacks 63 which may be located at any distance desired beyond the forward end of the mine track.

25 While the forward truck may be extended beyond the mine track the rear truck always remains on the mine track and therefore the rear ends of the ropes 62 may always be connected to the rail clamps as shown in Figs. 1 and 5. It can readily be seen that whenever it is practicable to do so it is easier to shift the positions of the rail clamps and lock them in adjusted positions than to shift the wall jacks 63 and secure them effectively in anchoring positions.

30 Obviously those skilled in the art may make various changes in the details and arrangement of parts without departing from the spirit and scope of the invention as defined by the claims hereto appended and it is therefore desired not to be restricted to the precise construction herein disclosed.

35 Having thus fully disclosed an embodiment of the invention, what is desired to be secured by Letters Patent of the United States is:

40 1. A rail clamp comprising a bar having cylindrical portions at opposite ends thereof, gripping members journaled on said portions and having offset jaws thereon, means for detachably securing one of said gripping members to said bar, an arm connected with the end of said bar opposite said detachable securing means for receiving the end of a cable, and an eccentric portion formed on said bar and arranged under the rail in position to grip a rail flange between said eccentric portion and said offset jaws when said arm is rotated by the tension exerted upon

45 said cable.

50 2. A rope anchorage adapted to be connected to the bottom of a rail to slide along the same to adjusted position, comprising clamping mechanism associated with the base flanges of the rail and a rock shaft extend-

55 ing transversely of the bottom of the rail for operating the clamping mechanism, and detachable means at one end of the rock shaft for enabling the rope anchorage to be quickly extended beneath the bottom of the rail between adjacent ties and connected to the bottom of the rail for operation by a rope connected to said rock shaft.

60 3. A rope anchorage adapted to be connected to a rail, comprising an actuating shaft, a clamping jaw journaled to said shaft in position to engage the outer base flange of the rail, a removable clamping jaw journaled on said shaft in position to engage the inner base flange of the rail, an eccentric cam on said shaft between said journal bearings in position to engage the bottom of the rail, and a removable device for retaining said second-named jaw on its journal bearing after

65 said shaft has been extended transversely of the bottom of the rail, and a lever for actuating said shaft and said cam.

70 4. An anchorage device comprising a rock shaft, an operating lever connected thereto, a clamping jaw journaled on said shaft in position to engage the upper outer surfaces of the base flange of the rail, an eccentric cam on said shaft in position to engage the bottom of the rail, a removable jaw journaled on said shaft in position to engage the upper side of

75 the inner base flange of the rail, and an inverted removable U-shaped key adapted to fit in transverse slots at the inner end of said shaft to detachably mount the anchorage device on the bottom of the rail.

80 In testimony whereof I have signed my name to this specification on this 8th day of September, 1928.

OLIVE EUGENIE MORGAN,
Executrix of Edmund C. Morgan, Deceased.
